ROBERT ZAHN, OF PLAUE, GERMANY; ALFRED RIETZSCH ADMINISTRATOR OF SAID
ZAHN, DECEASED.

JACQUARD MECHANISM FOR EMBROIDERING-MACHINES.

1,118,388.

Specification of Letters Patent.

Patented Nov. 24, 1914.

Application filed December 23, 1908. Serial No. 468,967.

To all whom it may concern:

Be it known that I, ROBERT ZAHN, subject of the German Emperor, residing at Plauen, in the Kingdom of Saxony and Empire of Germany, have invented certain new and useful Improvements in Jacquard Mechanism for Embroidering-Machines, of which the following is a specification.

The main object of the invention is to provide an apparatus permitting a much finer or minute control of the movements of the embroidery frame than is afforded by any of the apparatus hitherto known.

The apparatus constructed according to the present invention comprises a rocking lever mounted on a fixed axis, and an adjustable lever one end of which is connected by motion transmitting means with the embroidery frame, and the other end of which can be moved upon and fixed to the rocking lever at any desired distance from the center of rotation of the said rocking lever.

Apparatus embodying the improvements of the present invention, is illustrated by way of example in the accompanying drawings in which:

Figure 1 is a side elevation of the left-hand side of the machine; Fig. 2 is a plan thereof. Figs. 3 to 9 are drawn to a larger scale than Figs. 1 and 2. Fig. 3 is a cross-section approximately on the line A of Fig. 2, Fig. 4 is a side elevation looking in the direction of the arrow B and Fig. 5 shows the same parts looking in the direction of the arrow C. Fig. 5^a is a detail view of a portion of the construction shown in Fig. 5, on a larger scale. Fig. 6 is a plan of Fig. 5, and Fig. 7 is a section on the line D in Fig. 6. Fig. 8 is a section on the line E of Fig. 2 looking in the direction of the arrow F. Fig. 9 is a section on the line G of Fig. 8, and Fig. 10, which is drawn to a much smaller scale than Figs. 1 and 2, is a diagrammatic view of the general arrangement of the machine, shown in Figs. 1 to 9 coupled to an embroidering machine in such a manner that the desired movements are transmitted to the embroidering frame of the latter machine. Fig. 11 is a sectional elevation of a portion of the mechanism controlled by the jacquard card. Fig. 12 is a view of the mechanism shown in Fig. 11 in another position. Fig. 13 is a view of the product of the machine. Fig. 14 is a diagrammatic view of a portion of the mecha-

nism shown in Fig. 11. Fig. 15 is a diagrammatic view showing a different position. Fig. 16 is a diagrammatic view of the same mechanism showing a still further adjustment and position. Fig. 17 is a diagrammatic view of the same mechanism showing a further adjustment and position.

The jacquard card 1 (Figs. 2, 3, and 4) is moved by the rolls 2, 3, 4, 5, slowly step by step in the direction of the arrows H. The card is provided with round holes 6, punched in its edge for the purpose of regulating the exact step by step advance of the card, by the engagement of pegs 7, provided on the rolls 3 and 4. The rolls 2, 3, 4, 5, are rotated progressively step by step by means of wheel gearing not shown in the drawings.

On each of the two vertical shafts 8, 9, is rotatably mounted a feeler lever 10. As shown in Fig. 1, the shaft 8 (as also the shaft 9) has a shoulder 11. A ring 12 is pressed by a spring 13 down against this shoulder 11. The ring 12 is capable of moving vertically up and down along the shaft 8, but is not capable of rotating relatively to the shaft. A nut 14 is provided for pressing the collar 12 against the shoulder 11 with adjustable force, the spring 13 being tensioned more or less as required by screwing down the nut 14. The feeler lever 10 is loose, and capable of rotation on the shaft 8, but as the spring 13 exerts a pressure upon the feeler lever 10, the latter is compelled to swing to and fro in an arc of a circle when the shaft 8 is rotated to and fro. But if the end of the lever 10, strikes against any object, the shaft 8 can continue its rotation without compelling the lever 10 to overcome the obstacle. The movement of the lever 10, is thus effected by means of friction between the parts 11 and 12. At every working movement of the machine, the shaft 8 (as well as the shaft 9) is rotated forward and backward through a determined angle.

Just above the jacquard card 1 there is provided an arc-shaped guide 15 in which a small light slide 16 can be moved to and fro. This slide carries a horizontal pin 17 and a vertical part 18. As shown in Fig. 5, the lower end of this vertical part 18 is slightly beveled. A very weak sensitive spring 19 (Fig. 5) has a tendency to keep the part 18 down with slight force, so that

its lower end touches the surface of the card 1. The free end of the lever 10 has the shape of a fork 20, extending downward. This fork 20 embraces the pin 17, therefore 5 when the lever 10 swings to and fro on this shaft 8, (or 9) the small slide 16 and also the part 18 must share this to and fro swinging movement.

The card 1 is provided at determined 10 points with small punched elongated holes or slots 21 (pattern holes) situated exactly in the path of the part 18. When the lever 10 moves in the direction of the arrow J and in this movement the part 18 meets one 15 of the holes 21 it snaps into this hole and the feeler lever 10 can no longer rotate. But as the holes 21 are so small that the part 18 cannot sink down wholly in them, the lever 10 is able to rotate back again without hindrance in the opposite direction of rotation 20 on the next movement of the shaft 8. As shown in Fig. 5, the end of the part 18 is beveled and the said part will therefore spring out again from the small hole 21 in 25 which its point had sunk.

The following mechanism is now employed for the purpose of enabling the lever 10, which has been adjusted to the very slight resistance offered by the edge of the 30 hole 21 in the card, to resist the much greater force which is necessary for the purpose of moving the embroidery frame that weighs from about 400 to 500 kilogs. For this purpose the small slide 16 is 35 clamped by means of an eccentric device in the position into which it has been brought by the feeler lever 10. This is shown more particularly in Figs. 6 to 9.

The slide 16 is provided with a strip 22 40 that is bent upwardly and rearwardly in such a manner that it is situated just above the resisting plate 23, and just below a block 24. The block 24 can move vertically up and down relatively to the plate 23, so that 45 the strip 22 can be clamped in it, as it were in a vise. This up and down movement of the block 24 is produced as follows: The block is perforated with a cylindrical hole 50 throughout its length, and in this hole is a roll 25 with eccentric trunnions 26 and 27. When the roll 25 is rotated on its trunnions 26, 27, the block 24 is moved down, and 55 grips the strip 22. The under surface of the block 24 is roughened like a file, and is hardened; this increases the security of the grip on the strip 22. The eccentric roll 25, receives its rotation from a lever 28 which is fixed on its trunnion 27, and the upward movement of which is limited by striking 60 against the lever 29, and is acted upon by a spring 30 which has a tendency to draw the levers 28 and 29 constantly toward each other. The lever 29 is connected rigidly by its shaft 31 with a second lever 32, to which 65 is pivoted a rod 33. This rod 33, as shown

in Fig. 1, is operated by a lever 34 which receives at the proper moment a slight up and down motion from the main driving mechanism through the medium of a shaft 35. The rod 33 is not connected directly to 70 the lever 28, and it receives its motion indirectly through the lever 29 for a purpose hereinafter described.

On the vertical pin 36 there is mounted a 75 rocking lever 37, the right hand of which carries a vertical bolt 38, and an inwardly bent arm 39. The lever 37 is hereinafter referred to as the "adjusting lever," and the arm 39 is hereinafter referred to as the "adjusting arm." These two parts serve for adjusting the bolt 38 (whose function will be hereinafter described) to a determined point of the arc-shaped guide 40 when the end of the adjusting arm 39 strikes against the hereinbefore mentioned strip 22 and the latter is clamped in position by the eccentric block 24.

The striking of the adjusting arm 39 against the fixed strip 22 is effected by means of a small bolt 41 (Figs. 2, 5 and 6) 90 which is capable of vertical movement in the adjusting arm. This bolt 41 is held up from below by a small weak spring 42, and is influenced further by the fact that it is provided at its rear side with a slot 43 into which the front arc-shaped edge of a plate 44 engages. The edge is made arc-shaped because the bolt 41 whose slot is intended to move along the said edge, is mounted to swing on a pin 36 as a center. The said front edge of the plate 44 has thus the form of an arc of a circle described from the center 36. It may be stated, by the way, that the small slide 16 is likewise guided in an 95 arc of a circle in its path 15, which path is also described from the pin 36 as a center. This would appear at first glance to be a contradiction, because the lever 10 which moves the slide 16 to and fro, swings on another center, namely, the center 8. But the deviation of these two circular paths from each other is equalized by the fact that the pin 17 is made of suitable length, and is loosely embraced by the fork 20, so that as the lever 10 oscillates, the fork 20 will shift 100 to a slight extent on the pin 17.

The up and down movement of the bolt 41 is effected through the medium of the hereinbefore referred to driving mechanism 33, 110 32, 31, to which the peculiar lever arrangement 29, 28, is also connected. The aforesaid plate 44 is fixed on the same shaft 31, namely, the shaft on which the two levers 29 and 32 are rigidly fixed. Thus in whatever point of its path the bolt 41 may be situated, the said bolt, by reason of its engagement through the slot 43 with the plate 44, will always be raised and lowered at the same moment as the strip 22 is released and gripped again. But it is to be noted that 115 120 125 130

the bolt 41 will always be raised just before, that is to say, will be released from its contact with the strip 22, before the strip 22 itself is released out of its clamped position. 5 The reason is that this release takes place only when the lever 28 is pressed completely down, so as to allow the eccentric roll 25 to act.

As already above indicated the bolt 38 is 10 movable to and fro in an arcuate guide. This arc-shaped guide 40 occupies the position shown in Fig. 2 only at the moment when the bolt 38 is to be moved to and fro or is fixed in the said guide. In other 15 respects it forms the upper part of a vertical shaft 45 (Figs. 1, 8 and 9) which can be rocked to and fro through about 90° , by the very powerful force of the driving gear of the machine. This driving gear consists of 20 a lever, 46, fixed on the shaft, 45, a connecting rod, 47, and a slide, 48, of sufficiently strong construction. 49 is the main shaft of the machine, on which are fixed a large number of cams among which are the two 25 cams, 50 and 51. Rollers, 52 and 53 are pivoted on the slide, 48, the periphery of the cam, 50, being always in contact with the roller, 52, and that of the cam, 51, with the roller 53. Therefore when the main shaft, 30 49, rotates uniformly, the slide, 48, will be caused by the cams 50, 51, to move to and fro or to remain stationary at intervals. In the same way are produced the to-and-fro 35 rocking movements of the shaft, 45, and of the guide, 40, which is rigidly fixed thereto.

In the position of the parts shown in Fig. 2, the bolt, 38, is actually central with the shaft, 45. This is the basic position into which the lever, 37, is adjusted on every 40 working movement of the machine, by means of a driving mechanism hereinafter described. But if the lever, 37, is rocked to such an extent outward that its bolt, 41, strikes against the strip, 22, then the bolt, 38, assumes a position within its guide, 40, which is situated at a greater or less distance from the said basic position. When this shaft, 45, with the guide, 40, has rocked in the direction of the arrow J¹, (Fig. 2) the 45 lever, 37, which has up till then acted as an adjusting lever, now acts like a connecting rod and pushes back the bolt, 38, and all the parts connected with it to a corresponding extent. This movement of the bolt, 38, in 50 the direction of the arrow K (Figs. 1, and 2) is the movement, which is hereinafter described, serves for moving the embroidery frame from stitch to stitch. The great 55 pushing force produced by the cams, 50, 51, enables the said movement to move the great heavy mass of the embroidering frame, although the weak lever, 10, which serves to limit this movement, has only struck against the edge of the hole, 21, in the jacquard 60 card 1.

In the same way as the small part, 18, is held temporarily in its position by the clamping of the strip, 22, a similar process takes place with the much larger bolt, 38. The bolt, 38, (see Figs. 8 and 9) forms the 70 upper part of a link block, 54, which is guided in a circle in the guide 40, an eccentric roll, 55, acting against the lower edge of the said link block. The lever, 59, which is fixed on the journal, 57, serves to rotate 75 to and fro the eccentric roll, 55, which is rotatably mounted with its journals, 56, 57 in the head, 58, of the shaft, 45. The arm, 60, shown in Figs. 1, and 2, is not a movable lever, but it is fixed to or formed in one 80 piece with the head, 58, and it has merely the object of enabling the spring, 61, to be hung, which spring is put under tension when lever 59 and therefore also the eccentric roll 55 are rotated to the right, by the 85 lever 59 being moved away relatively to the arm 60 by the screw stop 62. The eccentric roll 55 is thereby released and the bolt 38 is freed for the purpose of being shifted, so long as the stop 62 forces back the lever 59, 90 as shown in Fig. 1. But when the lever 59 is free to follow the pull of its spring 61, it brakes and holds fast the bolt 38 wherever the latter may be situated in its guide 40.

In the diagrammatic Fig. 10, 63, 64, 65, 95 indicate the framing of a shuttle embroidering machine, in which the embroidery frame 66, 67, 68 is suspended in the ordinary manner so as to be capable of moving in all directions in its own vertical plane. The 100 frame is balanced by means of counterweights. In an ordinary shuttle embroidering machine this embroidery frame 66, 67, 68, is moved to and fro by means of a pantograph by the hand of the operator, but in the present case two shafts, namely, a vertical shaft 69 and a horizontal shaft 70 are employed for the same purpose, and are caused by the hereinbefore described mechanism to rotate to and fro. In these movements a 105 pinion 71, fixed on a shaft 69, gears with a horizontally movable rack 72 having on its left end a guide 73.

On the embroidery frame 66, 67, 68, there is fixed a triangular arm 74 carrying a guide 115 pin 75. The pin 75 engages in the guide 73. On the shaft 70 there is also fixed a pinion 76, which engages with the rack 77, that can move vertically up and down. On the upper end of the rack 77 is provided the 120 guide 78, in which there also engages the aforesaid pin 75.

Assuming that the shaft 70 is held fast for a moment, that is to say, it does not rotate, and that the shaft 69 rotates through 125 a certain angle, then the pin 75 will be moved in a horizontal direction by the guide 73 through the medium of the toothed wheel gearing 71, 72, and consequently the whole embroidery frame 66, 67, 68, must share this 130

horizontal movement. As assumed above the guide 78 is stationary at this moment, and therefore the pin 75 slides in this guide, that is to say, the embroidery frame has itself no vertical movement. Now if on the other hand, the shaft 69 be held fast for a moment, and the shaft 70 be rotated, then the pin 75 and consequently the entire embroidery frame will only move vertically up and down, and the pin 75 will slide in the vertical guide 73. If the two shafts 69 and 70, are rotated simultaneously, then obviously the pin 75 will be guided by the two guides 73 and 78 in an oblique direction, and the embroidery frame 66, 67, 68, will move in this oblique direction. Thus, the angles of rotation and the direction of rotation of the two shafts 69, 70 will always determine the movement of the embroidery frame in any direction, horizontal, vertical, or oblique.

Referring to Figs. 1 and 2, it is to be noted that the holes 21, in one half of the jacquard card 1, have the function of regulating the movements of the vertical shaft 69 for the horizontal movements of the embroidery frame, and that the holes 21 in the other half of the jacquard card have the function of regulating the movements of the horizontal shaft 70 for the vertical movements of the embroidery frame. For this reason all parts are provided in duplicate and arranged symmetrically in Fig. 2 as already stated, although not all the parts are shown in that figure for the sake of simplifying the drawings. Obviously, the mounting and drive of the two shafts 69 and 70, constitute exceptions from the symmetrical arrangement. This drive is as follows:—and will now be described first in the case of the vertical shaft 69 for producing the horizontal movements of the embroidery frame:—The pin 36 which, as already above stated is moved horizontally to and fro, causes a corresponding to and fro movement of a slide 79, 80, 81, 82. The said slide is guided in a horizontal straight line by any suitable means. On the shaft 69, there is fixed a disk 83 against the periphery of which, the slideways 84 and 85 can be pressed alternately by means of an eccentric roller 86. These slideways are adapted to rock through a very small angle on their pins 79, 80, and are connected together by means of a coupling link 87. When, as assumed in Fig. 2, the slideway 84 is pressed against the friction disk 83, that is to say, the slideway 85 is free, and the pin 36 moves in the direction of the arrow H, the shaft 69 will be rotated to the right, and the embroidery frame 66, 67, 68, (Fig. 10) will move horizontally in the corresponding direction. But if instead of the slideway 84, the slideway 85 is pressed by the eccentric roller 86 against the periphery of the disk

83, then the pin 36 is moving in the direction of the arrow K, the shaft 69 will rotate in the opposite direction, that is to say, to the left.

Exactly the same driving mechanism as that just described (83, 84, 85, 86) is also provided for driving the horizontal shaft 70, that is to say for producing the vertical movements of the embroidery frame. This driving apparatus is indicated in Fig. 1 by 83', 84', 85', 86'. Both the driving mechanisms differ from each other only by the fact that they are turned through an angle of 90° relatively to each other. The driving of the eccentric roller 86 will be hereinafter described.

On the main shaft 49 there are fixed a large number of eccentrics of which these 50, 51, have already been referred to. The other eccentrics are not shown in order to prevent overcrowding of the drawing. On the periphery of one of these eccentrics that are not shown, there works the roller 88, which is pivoted in the lever 89 and can rock on the shaft 90. On this shaft 90 is also fixed the forked lever 91, 92. 91 is the lever on which the screw stop 62 is mounted. The lever 92 is provided with a nose designed to work against a hook 93 which forms the end of an arm 94. This arm 94 forms a part of the hereinbefore mentioned slide to which the pin 36 belongs. The engagement between the lever 92 and the hook 93 is to compel the pin 36 to move exactly into the terminal point of its horizontal path (if it should not be there already) at a certain moment of the operation of the machine. This terminal point of the path forms at the same time the exact rocking center of the arc-shaped guide 40, along which the bolt 38 must be guided. But when the pin 36 has been secured at this center by the engagement of the parts 92, 93, the lever 91 has also depressed the lever 59, that is to say, the eccentric roll 55, (Figs. 8 and 9) has released the bolt 38 which can now slide along the slideway 40 until the bolt 41 strikes against the strip 22. I shall now proceed to describe how this rocking movement of the bolt 38 on the center 36 can take place in such a manner that it will cease when the part 41 strikes against the part 22. This is effected in the same manner as already described with reference to the feeler lever 10, which had to be suddenly held in a variable point of its path namely, by frictional drive. The lever 37 which rocks on the pin 36 and the outer end of which carries the bolt 38 and the adjusting arm 39 with the bolt 41, forms one rigid piece with the lever 95. This lever 95 carries at its end a leather covered pair of tongs 96, 97, (Fig. 1), which are held together by spring pressure and which hold a straight rod 98. The rod 98 is connected by a universal joint with 130

the lever 99, which is fixed on the shaft 100. The shaft 100 is rocked by means of an eccentric on the main shaft 49, forward at one moment, and backward at another moment. 5 The bell crank lever 95, 37, which rocks on the pin 36 will therefore also be compelled generally to follow the drive of the lever 99. But from the moment that the bolt 41 strikes against the strip 22, this drive ceases, 10 and the leather covered tongs 96, 97, slip along the rod 98 during the remainder of the movement of the lever 99.

I shall now proceed to describe how the above mentioned eccentric rollers 86, and 86' 15 are rotated in one or the other direction, in order that at one time the slideway 84 and at another time the slideway 85 shall be pressed against a friction disk 83. This drive must obviously also be regulated by 20 means of the jacquard card 1. For this purpose there are punched in the jacquard card at certain places holes 101, which serve to allow of the passage of a small nose 102 (Fig. 3). On each stroke this nose 102 is 25 pressed by the hereinafter described mechanism, with very small force in an upward direction. If in this upward movement the nose does not meet any hole 101, in the card, it remains down, and therefore does not produce the action which would cause a rotation 30 of the eccentric roller 86.

Between the rolls 3 and 4, there is arranged a stationary table 103. The jacquard card 1, moves closely over this table. 35 Below the table 103 and near the two edges of the jacquard card there is arranged a plate 105 which rocks on the pin 104, and is provided at the top with the nose 102 and rests at bottom on a small lever 106, rocking 40 on the pin 107. By means of a mechanism which is moved by one of the eccentrics mounted on the main shaft 49, there is moved a pin 108 to and fro in a horizontal direction at each working stroke.

45 The pin 108 is in contact on one side with the lever 106, and on the other side with a weak spring 109 fixed to the lever 106. If now, the pin 108 (Fig. 3) moves to the right, it carries with it the lever 106, the upper end 50 of which strikes against the nose 110 of the plate 105, whereby the nose 102 is compelled to move down that is to say, to move out of the hole 101 in the jacquard card. But if the pin 108 is moved to the left in 55 Fig. 3, two things can happen. If the nose 102 meets with a hole in the jacquard card, then the lever 106 is compelled by the small spring 109 to follow this movement of the pin 108 to the left, and it pushes up the plate 60 105 so that the nose 102 passes through the hole in the card. Or, if the nose 102 does not meet with a hole in the card, then the lever 106 is unable to move the plate 105 upward, that is to say, the lever 106 remains 65 behind, the spring 109 yields, because the

upper end of the lever 106 meets with resistance from the plate 105 as shown in Fig. 12.

When the pin 108 is moved from the position shown in Figs. 3 and 11, toward the right back into its normal position, then it moves 70 the lever 106 with it, and the upper end of the lever 106 strikes against the nose 110 of the plate 105, forces it back and thereby compels the nose 102 to move down again out of the hole of the jacquard card 1. 75

A rod 111 is moved at each working stroke once horizontally to and fro in the direction of its own length, exactly in the direction in which the nose 102 appears now and again over the top of the jacquard card 1. 80 If in this case the front end of the rod 111, meets the projecting nose 102, it strikes against it and cannot move any farther. If on the other hand it does not meet it, that is to say, the nose 102 is not projecting 85 through the jacquard card, then the rod 111 will continue its full stroke without hindrance. This movement of the rod 111 and the hindering of its movement by means of the nose 102 takes place as already indicated above, for the purpose of operating the eccentric rollers 86, 86' shown in Figs. 1, and 2, in such a manner that the right and left hand rotary movements of the vertical shaft 69 shall be guided in accordance with the 90 design to produce the horizontal movements of the embroidery frame, and the right and left hand rotary movements of the horizontal shaft 70 shall be guided in accordance with the design to produce the vertical 100 movements of the embroidery frame.

I shall now describe the driving mechanism for producing the to-and-fro movements of the rod 111, and the transmission of the movements to the eccentric rollers 86 105 and 86'.

In the front part of the framing of the machine there are mounted two shafts 112 and 113 (Figs. 2, 11 and 12). On the shaft 112 is fixed a lever 114, on the free end of 110 which there is mounted the roller 115, which is assumed to bear on the periphery of an eccentric that is fixed on the main shaft 49 (Fig. 1). On the shaft, 112, there is further fixed a lever, 116, with a roller, 117. 115

A three armed lever in which are arranged pivoting bolts, 118, 119, 120, is rotatably mounted loose on the shaft, 112. On the shaft, 113, there is also similarly mounted a two armed lever provided with pivoting bolts, 121, 122. The two pivoting bolts, 119, 122, are movably jointed together by means of a three armed connecting piece. It is to be understood that only one of the bolts 118 and 123 is in use at the same time, 125 the other being removed to leave the parts disconnected. A connecting rod, 124, is provided likewise with two bolt holes, 118' and 123' for insertion of bolts 118 and 123, and this rod serves to make a connection with 130

the eccentric roller, 86 (Figs. 1 and 2). According as the pivoting bolt is inserted into the hole 118', or into the hole 123', then, at a determined movement of the mechanism shown in Figs. 11 and 12, the connecting rod, 124 is moved to and fro in one or the other direction, and consequently either the slideway, 84, or the slideway, 85, is pressed against the periphery of the roller, 83, and 10 produces right hand or left hand rotations of the shaft, 69. Another connecting rod, 124', (Figs. 1 and 2), making connection with the eccentric roller, 86', and acting in a similar manner as the rod, 124, serves to 15 cause either the slideway, 84', or the slideway, 85', to be pressed against the periphery of the roller, 83', for producing right hand or left hand rotations of the shaft, 70.

In the front upper part of the framing of 20 the machine there is mounted a shaft, 125, shown in Figs. 1, 2, 11, 12, 14, 15. By means of a lever and eccentric (not shown in the drawings) worked from the main shaft 49, the shaft, 125, is rocked to and fro 25 through a small angle once at a certain moment on each working stroke, so that the two levers, 126, which are mounted right and left in the machine on the shaft, 125, are moved once up and down at each working 30 stroke. The free ends of the two levers, 126, are connected together by a rod, 127.

Two vertical connecting rods, 128 and 129, are each provided at their upper end with a semi-circular recess by which the said rods 35 can be alternately hung onto or coupled with the rod, 127. In Figs. 1, 11 and 14 the rod, 128, is shown by way of example hung onto the rod, 127. In Figs. 12 and 15 the rod, 129, is shown so coupled. Now whichever 40 rod (128 or 129) is hung onto the rod, 127, that rod must follow the movement of the lever, 126. The fact which of the two rods, 128 or 129, is to be coupled to the rod, 127, is controlled by the rod, 111 co-operating 45 with the nose, 102, which projects now and then above the surface of the jacquard card, 1.

The rod, 111, is movably connected by means of the pivoting bolt, 130, to the rod, 50 128, and the rod, 129, is pulled by a spring, 131, toward the rod, 128, and the rod, 129, being maintained by means of a nose, 132, on the rod, 129. A spring, 133, pulls the rod, 128, 55 to the left until the slideway 134 arranged on rod 128 strikes against the roller 117 of the lever 116.

The operation is somewhat as follows:— At each working stroke the lever 116 moves 60 once for a short distance to the left and to the right. The two levers 128 and 129 are caused by the two springs 133, 131 to follow this left and right movement of the lever 116, when the nose 102 is not projecting up through the jacquard card 1. But

if the nose 102 does so project, the rod 111 strikes against the nose and in opposition to the spring 133, prevents the lever 126 from following the movement of the lever 116 to the left. In this case the roller 117 70 will move away from the slideway 134. At the same moment when the nose 102 is holding the rod 111, the lever 126 makes a small upward movement and, since the rod 128 is hung on to the rod 127, the rod 128 75 will be drawn up with it. This position of the parts is shown in Fig. 14. But if the nose 102 was not projecting up through the card 1, then not the rod 128, but the rod 129 is coupled to the rod 127, and the 80 rod 128 remains down, while the rod 129 is drawn up. This position of the parts is shown in Fig. 15.

In the foregoing description, it has been assumed that the pivoting bolt 123 was 85 inserted in the hole 123'. But if the pivoting bolt 118 was inserted in its pivoting hole 118', then the same movements as described in reference to Figs. 14 and 15 will take place with the result shown in Figs. 16 and 90 17. The difference consists obviously in the fact that the rod, 124 in Fig. 16, is making the opposite movement to that shown in Fig. 14, and is making in Fig. 17, the opposite movement to that in Fig. 15. It will therefore be understood that when, for example, it is desired to embroider a design such as that indicated at *a* in Fig. 13, in the way shown and in the symmetrical but opposite way *b*, it is merely necessary to insert the 100 aforesaid pivoting bolt at one time at 118' and at the other time at 123', into the pivoting joint, on the side of the machine controlling the horizontal movements of the embroidery frame, the vertical movements 105 of the latter remaining unaltered.

The design *d* is obtained by reversing the vertical movements of the frame without reversing its horizontal movements and the design *e* by reversing both the vertical and 110 the horizontal movements of the frame. By these means it is thus possible to embroider one and the same design in four different positions from a single jacquard card, that is to say, a jacquard card which has been 115 punched only with one design.

Having now particularly described and ascertained the nature of my said invention, and in what manner the same is to be performed, I declare that what I claim 120 is:—

1. An embroidering machine comprising in combination, a jacquard, an embroidering frame, devices connected with said frame and adapted to shift the same in a plurality of different directions, and driven mechanism controlled by the jacquard and connected with said devices and including a shifting and rocking lever having a fixed axis, an adjusting lever for transmitting 125 130

motion to said frame, and means controlled by the jacquard for anchoring said adjusting lever to said rocking lever at any desired distance from the rocking axis thereof, substantially as described.

2. An embroidering machine comprising in combination, a jacquard, an embroidering frame, devices connected with said frame and adapted to shift the same in a plurality of different directions, driven mechanism controlled by the jacquard and connected with said devices and including a rocking lever having a fixed axis, an adjusting le-

ver for transmitting motion to said frame, and means controlled by the jacquard for anchoring said adjusting lever to said rocking lever at any desired distance from the rocking axis thereof, substantially as described.

In testimony whereof I affix my signature in presence of two witnesses.

ROBERT ZAHN.
